TYPEWRITING MACHINE

Filed Aug. 29, 1923

UNITED STATES PATENT OFFICE

JOHN WALDHEIM, OF ELIZABETH, NEW JERSEY, ASSIGNOR TO UNDERWOOD ELLIOTT FISHER COMPANY, OF NEW YORK, N. Y., A CORPORATION OF DELAWARE.

TYPEWRITING MACHINE

Application filed August 29, 1923. Serial No. 659,913.

This invention relates to machines for typ-
ing upon continuous work-webs, each com-
prising a plurality of plies usually provided
with successive printed forms superposed in
register, the plies being separate in some cases
and in other cases being joined at their side
edges. The invention is in the nature of an
improvement on my Patent No. 1,362,547,
dated December 14, 1920.

10 In said patent the composite web or work-
web, comprising the web-plies, is introduced
substantially horizontally to the bottom of
the platen, over a table or support on which
the carbon-carrier is mounted for reciproca-
15 tion, and over a substantially horizontal
paper-table to support the web between the
forward end of the carbon-carrier support
and the bottom of the platen, thus eliminat-
ing the binding of the web-plies and inter-
20 leaved carbon-sheets due to the usual bends
in the web at the rear of the platen. Pro-
vision is also made for reducing the bending
of the web-plies at the delivery side of the
platen by swinging forwardly to a limited
25 extent a paper-table and an associated lead-
ing-end-gaging device independently of the
platen. As a result of the arrangement just
described, it becomes unnecessary to displace
the platen in the usual manner preparatory
30 to effecting a relative shifting of the web-
plies and interleaved carbon-sheets.

An object of the present invention is to
provide improved means of the same general
35 nature as that described for effecting such
relative shifting of the web-plies and carbon-
sheets without displacement of the platen or
forward swing of the paper-table and gaging
means at the delivery side of the platen.

According to the form of the invention
40 herein disclosed, the web-and-carbon-sheet-
introducing means at the introductory side
of the platen is substantially the same as in
said patent, and provision is made at the
delivery side of the platen of a paper-table
45 fixed to the platen-frame, and of a gaging
device having two gages at a suitable distance
apart such that, when, after the release of
the feed-rolls, the web-plies and interleaved
carbon-sheets are shifted rearwardly by the
50 carbon-carrier to withdraw the leading ends

of the carbon-sheets from control by the
platen, the feed-rolls may be cast on, the web-
plies advanced independently of the carbon-
sheets by the platen to bring the leading ends
55 of the web-plies into alignment with the near-
est gage, and then the web-plies and carbon-
sheets may be advanced together until the
leading edges of the web-plies are aligned
with the other gage preparatory to tearing
60 off the first set of forms and typing on the
second set of forms.

Provision may also be made of one or more
side gages to be set in suitable perforations
in the rear paper-table over which the web-
plies pass from the carbon-carrier support
65 to the bottom of the platen. Preferably each
side gage has a forked lower end to permit
springing of the tines when forced into posi-
tion and consequent binding to maintain the
side gage in such position.

70 Other features and advantages will herein-
after appear.

In the accompanying drawings,

Figure 1 is a sectional side elevation of a
portion of an Underwood continuous billing
75 typewriting machine modified to show one
form of the invention.

Figure 2 is a view similar to Figure 1, but
showing the carbon-sheets and web-plies in
the positions assumed when retracted by the
80 carbon-carrier after completing the typing on
a set of forms and casting off the feed-rolls.

Figure 3 is a view similar to Figure 2, but
showing the web-plies advanced relatively to
the carbon-sheets by the platen and cast-on
85 feed-rolls, the carbon-sheets being held
against forward movement by means of the
carbon-carrier.

Figure 4 is a view similar to Figure 3, but
showing the web-plies and carbon-sheets ad-
90 vanced by the platen and feed-rolls from their
Figure 3 positions to positions suitable for
tearing off the typed forms.

Upon depression of keys (not shown),
type-bars 11 are swung upwardly and rear-
wardly to cause types 12 thereon to strike a
platen 13, journaled by means of an axle 14
95 in the ends 15 of a platen-frame 16. The
ends 15 of the platen-frame are joined at the
rear by a transverse member 17 and beneath
100

the platen by means of a rod 18, on which are mounted levers 19, carrying rear and front feed-rolls 20 and 21, respectively, the effectiveness of the feed-rolls being controlled by means of a controlling shaft 22 extending between downwardly-projecting ends 23 of the levers 19. The controlling shaft 22 is controlled in the usual manner by a cast-off finger-piece 24 connected thereto by means of a link 25, pivoted to an arm 26, fixed on the shaft 22.

The platen-frame 16 is mounted in a traveling carriage 27, supported at its rear on a rail 28, fixed to the machine-frame 29. The carriage 27 comprises ends 30, connected at their rear by a transverse member or bar 31. Fixed on the bar 31 are upwardly-extending brackets 32, in which is journaled a shaft 33, having fixed thereon arms 34 engaging pins 35 in the ends 15 of the platen-frame to assist in guiding the platen-frame 15 in its case-shift movements. Mounted on the bar 31 is a substantially horizontal paper-table 36 to direct work-webs between the platen 13 and a paper-apron 37 at the bottom of the platen. Provision is also made of a guide 38, secured to the brackets 32 above the paper-table 36, and the rear edges of the paper-table 36 and the guide 38 are flared in opposite directions 39 to assist in introducing web-plies 39 and interleaved carbon-sheets 40 beneath the platen. It should be understood that the web-plies 39, which constitute a work-web 41, may be entirely separate or may be joined at their edges.

The carbon-sheets 40 are attached at their rear ends to carbon-blades 42 projecting between successive web-plies 39 and supported in the usual manner on stepped blocks 43 mounted on a plate 44 constituting the main part of a carbon-carrier 45. The carbon-carrier 45 is mounted for forward and rearward motion by means of grooved rolls 46 journaled at the lower side of the plate 44 and engaging the edges of flat rails 48 forming a part of a rearward extension or table 49, which comprises forwardly and rearwardly extending rods 50 and front and rear transverse rods 51 and 52, respectively.

The forward end of the extension 49 is connected with the carriage 27 by means of brackets 53 connecting the front rod of the extension with the brackets 32 on the carriage 27. At its rear, the extension 49 is supported on a fixed rail 54 by means of rolls 55 resting thereon and pivotally mounted on brackets 56 secured to the rods 50, each bracket having its lower end extending forwardly beneath the rail 54 to prevent the roll 55 from being lifted therefrom. The web 41 is led upwardly from any suitable source of supply and is turned at the rear of the extension 49 over a guide or rod 57 supported on arms 58 projecting upwardly from the

rod 52, provision being made of suitable side-edge gages 59 mounted on said rod 57.

The structure thus far described is substantially the same as the structure disclosed in said Patent No. 1,362,547, except that the rails 48 are lengthened. In the patent, however, the usual front paper-table and gage device are swung forwardly to reduce the curvature around the platen; whereas, according to the present invention, no such straightening of the work-web is required, the relative displacement of the web-plies 39 and the carbon-sheets 40 being effected in the same general manner as in my prior applications, Serial No. 642,961, filed June 2, 1923 (now Patent No. 1,574,215, dated February 28, 1926), and Serial No. 658,502, filed August 21, 1923 (now Patent No. 1,597,846, dated August 31, 1926).

In the form of the invention herein disclosed, provision is made of a paper-table 60, at the delivery side of the platen, having downwardly-turned ears or brackets 61 attached to the ends 15 of the platen-frame 16, and having attached thereto at its rear a gage bar or staff 62, on which is slidably mounted a gaging device 63 comprising a gage 64 to gage the forward ends of the work-plies when advanced relatively to the carbon-sheets with the latter in their retracted positions and a second gage 65 to determine the initial position of the web-plies and carbon-sheets for beginning the typing of another set of forms. The gaging device 63 is adjustable along the gage-bar 62 to correspond to different lengths of forms and may be secured at any position along said gage-bar 62 by means of a set-screw 66.

It is desirable to be able to use the gaging device 63 with short forms, and, as herein disclosed, this result is obtained by providing the staff 62 with an offset 68 to bring the upper end of the staff to the front of the plane of the table 60 and by providing a cut-out 69 in the table to receive said gage 64.

When it is desired to type on the work-web 41, the forward end of the web is passed over the guide 57 and forward over the table or extension 49, and the carbon-sheets 40 are interleaved between the plies 39 with their leading ends to the rear of the leading ends of the web-plies 39. The forward ends of the web-plies 39 may then be inserted beneath the platen and advanced by the platen and feed-rolls until the leading edges of the plies 39 are in alignment with the gage 64, the position of which is determined by adjusting the gaging device 63 with the gage 65 at a distance from a knife 70 equal to the length of one of the forms on the web 41.

During such advance of the web-plies 39, the carbon-carrier 45 is held by means of a handle 71 thereon in its rearmost position determined by a stop 72. In this connection it should be noted that the carbon-sheets 40

are of such length that, when the carbon-carrier is in its rearmost position, the leading ends of the carbon-sheets are positioned substantially as shown in Figure 3.

5 After positioning the web-plies 39 and the carbon-sheets 40, as shown in Figure 3, the carbon-carrier 45 is released and the web-plies and carbon-sheets advanced by the platen and feed-rolls to the positions indicated in Figure 4.

10 The first set of forms is then severed by the knife 70 and thereafter is in readiness for typing on the second set of forms. After completing the typing on the second set of forms with the web-plies and carbon-sheets positioned substantially as indicated in Figure 1, the feed-rolls 20 and 21 are cast off, by means of the finger-piece 24, and the web-plies 39 and carbon-sheets retracted, by 15 means of the handle 71 on the carbon-carrier, to the position shown in Figure 2. The feed-rolls are then cast on and the web-plies advanced by the platen to their Figure 3 positions, the carbon-sheets being held in their 20 retracted positions by means of the handle 71. The handle 71 is then released and the web-plies and carbon-sheets advanced to their Figure 4 positions preparatory to severing the typed forms and starting the typing 25 on the next set of forms. In this connection it should be noted that the distance between the gages 64 and 65 is equal to the distance around the bottom of the platen from the leading-edge positions of the carbon-sheets 30 in Figure 3 to their leading-edge positions in Figure 4.

35 Although the manner just described of positioning the web-plies and carbon-sheets to start typing appears to be the most practicable, it should be understood that such positioning may be done in other ways, as, for example, by positioning the forward edges of the first set of forms the proper distance beyond the ends of the carbon-sheets 40 and positioning the carbon-sheets and web-plies as shown in Figure 2. Obviously, if this method is followed, typing may be effected on the first set of forms.

45 To assist in guiding the composite web to the proper position on the platen, provision may be made of one or more side gages 73 positioned in suitable perforations in the rear paper-table 36. As shown in Figure 1, each of the gages 73 is provided with a slot 50 74 extending toward its upper end to facilitate the springing towards or from each other of the tines 75, so that, when the reduced ends 76 are pressed into suitable openings in the paper-table 36, the resiliency of the tines will tend to hold the gage in set position.

55 Variations may be resorted to within the scope of the invention, and portions of the 60 improvements may be used without others.

Having thus described my invention, I claim:

1. A gage-device for a continuous billing typewriting machine of the class described having a platen-frame, a platen, and a paper-table fixed on said platen-frame at the delivery side of said platen, including an upwardly-extending gage-bar fastened on said paper-table, an upper transverse gage adjustable along said gage-bar and projecting 70 forwardly therefrom, and a lower gage consisting of the lower end of a bar, which bar is fastened to said upper gage and extends downwardly along said gage-bar and parallel thereto a short distance to one side and 75 in the rear thereof, whereby the leading end of a work-piece in said machine may be first gaged by the lower gage and thereafter be conveniently advanced past said lower gage to be gaged by the upper gage. 80

2. In a continuous billing typewriting machine, the combination of a platen-frame, a platen, means for feeding work-plies in a straight condition to the bottom of the platen from the rear, a paper-table fixed on said platen-frame above the printing line of said platen, a knife fastened on the front of said paper-table above the printing line of said platen, an upwardly-extending gage-bar fastened on said paper-table, and an adjustable 90 gage-device on said bar, including an upper cutting-off gage projecting forwardly from said bar, and a lower gage disposed at a fixed distance from said upper gage and in the rear of said gage-bar, whereby work-plies having forms printed thereon may be gaged by said lower gage and thereafter be moved up past the lower gage to said upper gage, the arrangement of said means and 95 said gages requiring only one bend in the work-plies. 100

JOHN WALDHEIM.
